DESIGN FOR AN EMBLEM PLATE FOR AN AUTOMOBILE

Albert R. Willoughby, Indianapolis, Ind.

Application August 6, 1947, Serial No. 140,729

Term of patent 3½ years

(Cl. D14—6)

To all whom it may concern:

Be it known that I, Albert R. Willoughby, a citizen of the United States of America, residing at Indianapolis, in the county of Marion and State of Indiana, have invented a new, original, and ornamental Design for an Emblem Plate for an Automobile, of which the following is a specification, reference being had to the accompanying drawing, forming a part thereof. The drawing is lined for the colors blue and red.

Fig. 1 is a front elevational view of an emblem plate for an automobile, embodying my invention, and

Fig. 2, a top plan view thereof.

The characteristic features of the design reside in the features shown in full lines in the drawing.

I claim:

The ornamental design for an emblem plate for an automobile, substantially as shown and described.

ALBERT R. WILLOUGHBY.
